UNITED STATES PATENT OFFICE

JOHN B. BAXTER, OF TROY, NEW YORK, ASSIGNOR TO COVERT MANUFACTURING COMPANY, OF WATERVLIET, NEW YORK, A CORPORATION OF NEW YORK

SNAP HOOK

Application filed May 6, 1929. Serial No. 360,947.

This invention relates to improvements in snap hooks of the kind known as "bolt snaps" comprising a tubular body or barrel in which slides a spring pressed bolt cooperating with 5 a hook at one end of the tubular body or barrel and having a thumb piece for operating the same, the tubular body or barrel being provided in its forward part at the upper side thereof with a longitudinal slot 10 for the shank of the thumb piece.

In the use of snap hooks of the kind referred to, the forward portion of the bolt that normally closes the mouth of the hook and is usually formed of reduced diameter 15 and tapering, exerts an outward wedging pressure upon the forward slotted end portion of the tubular body or barrel which causes a gradual opening or spreading apart of said forward slotted end portion so that 20 the sliding bolt is left loose at the forward end of the slot free for upward play out of proper alignment with the bill of the hook. This, as will be appreciated, seriously lessens the efficiency of the device.

25 An object of the invention is to improve the manufacture of snap hooks of the general type referred to, to provide an improved bolt snap in which the tubular body or barrel is so formed as to close the slot at the forward end of the barrel and prevent opening or separation of the same by the bolt.

30 A further object of the invention is to provide an improved bolt snap having the longitudinal slot in the tubular body or barrel 35 closed at the forward end thereof, which will be strong, durable and efficient in use, and of simple construction, that can be easily produced at low cost.

35 The invention, with other objects and advantages thereof, and the particular construction, combination and arrangement of parts comprising the same, will be understood from the hereinafter contained detailed description when considered in connection with the accompanying drawings forming part hereof and illustrating one embodiment of the invention.

In the drawings:
50 Figure 1 is a top plan view of a bolt snap

constructed in accordance with the present invention.

Fig. 2 is a side elevation, partly in section.

Fig. 3 is a top plan view of the casting or blank.

Fig. 4 is a section on the line 4—4 of Figure 3.

Fig. 5 is a section on the line 5—5 of Figure 2.

Referring to a detail description of the particular embodiment of the invention illustrated in the drawings, 1 designates the tubular body or barrel having a hook 2 at one end and an attaching eye or loop 3 at its other end. 4 is a bolt slideable within the tubular body or barrel 1, having a tapered forward end portion 5 and provided with a thumb piece 6 which projects outwardly through the longitudinal slot 7 in the forward portion of the tubular body or barrel. 8 designates a coiled spring interposed between the rear wall 9 of the tubular body or barrel 1 and the rear end of the bolt 4. The tubular body or barrel is of the general construction known as the "cored" type cast with a core the peripheral wall of the rear portion of the tubular body or barrel being solid throughout.

The tubular body or barrel is preliminarily formed as illustrated in Figure 3 of the drawings with the opposing side walls of the slot 7 forwardly diverging, with the forward end portion of the barrel open adjoining said slot, and provided with spaced lateral extensions 10, 11, positioned one in advance of the other in staggered relation. This, as will be understood, permits of the ready insertion of the coiled spring 8 and bolt 4 within the tubular body or barrel 1, and after this has been performed, the forward portion of the tubular body or barrel at opposite sides of the slot 7 are forced toward each other by lateral pressure to bring together the staggered lateral extensions 10, 11, in close overlapping relation to close the slot 7 at the forward end of the barrel and to bring the opposite side walls 9 of the slot in parallel relation.

The special construction set forth provides a bolt snap in which the longitudinal slot in the tubular body or barrel is closed at the forward end thereof, the overlapping exten- 100

sions 10, 11, serving to close the slot and to strengthen the forward slotted portion of the tubular body or barrel, the resulting structure being of an efficient, strong, durable nature that will prevent spreading of the forward portion of the tubular body or barrel, the improved structure being such as to be easily manufactured and assembled.

What I claim is:

10. 1. A bolt snap comprising a tubular body or barrel with a hook at one end thereof and having a longitudinal slot in its upper side at its forward part, a bolt slideable in the tubular body having a thumb piece projecting outwardly through the slot therein, and a spring in the tubular body between the back wall thereof and the inner end of the bolt, and said body or barrel having staggered extensions projecting from opposite side marginal portions thereof forwardly of the slot, said staggered extensions being disposed in close overlapping relation and closing the slot at approximately the forward end portion of the barrel.
15. 2. A bolt snap casting including a tubular body or barrel part with a hook at one end thereof and having a longitudinal slot in its upper side at its forward part, the opposing side walls of said slot diverging from the rear to the front thereof, said body or barrel part at its forward end portion being open adjoining said slot and having spaced staggered lateral extensions projecting from opposite side marginal portions thereof forwardly of the slot, whereby a longitudinally extending guide slot closed at the forward end portion of the barrel will be provided when the opposite sides of the barrel part at the forward end portion thereof are forced laterally toward each other.
20. 3. In the manufacture of bolt snaps, the method of forming a tubular body or barrel with a hook at one end thereof and with a longitudinal guide slot in its upper side at its forward part with the opposing side walls of the slot diverging from the rear to the front thereof, and with the forward end portion of the barrel open adjoining said slot and with a lateral extension projecting from one side of its open end portion forwardly of said slot, and subsequently, after the insertion of the bolt within the barrel, forcing the opposite sides of the slotted portion of the barrel at the forward end portion thereof laterally toward each other to complete the forming of the guide slot and bring said lateral extension into position to substantially bridge and close the slot at approximately the forward end of the barrel.
25. 4. In testimony whereof I hereunto affix my signature.

JOHN B. BAXTER.
